W. P. Ware.
Ear, Cheek and Chin Muff.
No 20,834. Patented July 6, 1858.

UNITED STATES PATENT OFFICE.

W. P. WARE, OF CINCINNATI, OHIO.

EAR, CHEEK, AND CHIN MUFF.

Specification of Letters Patent No. 20,834, dated July 6, 1858.

To all whom it may concern:

Be it known that I, WILLIAM P. WARE, of the city of Cincinnati, in the county of Hamilton and State of Ohio, have invented 5 a new and useful Improvement in what I denominate an "Ear, Cheek, and Chin Muff;" and I do hereby declare that the following is a full, clear, and exact description thereof, reference being had to the accompanying drawings, and to the letters of reference marked thereon, and made to form 10 part of this specification.

Similar letters refer to like parts of the improvement.

15 The object of my improvement is to muff the ears, cheeks, and chin to protect them from cold without attaching or tying the article used for muffing on the top of the head or around the neck and face as is commonly done. And the nature of the improvement consists in making what I will here denominate pockets for each ear by taking a ring or frame of wire or other material and covering it with fur or other substances with such a fullness as to form a pocket in which the ears are placed for the double purpose of protecting them from the cold and supporting and holding the cheeks and chin portion of the muff to their respective parts as is fully represented in the accompanying drawings.

20 To enable others skilled in the art to make and use the improvement I will proceed to describe its construction and use.

25 Figure 1, represents a longitudinal sectional view of an improved muff, showing the pockets and a frame of wire and jointed for folding and to which the muffing mate-

rial or fur is attached. Fig. 2, is a similar view of another muff without the frame of 40 wire from ear to ear, as represented in Fig. 1, but rings are used as represented in Fig. 3, to assist in forming the ear pockets, and Fig. 4, represents a head, showing the use and mode of attaching the muff.

45 *a, a*, is a frame of wire jointed at (B) under the chin and (C, C,) at the lower part of the ear pockets for folding the muff up to make it as portable as possible.

50 *(d, d)* are the ring portions of the muff frame to which the pockets (*f, f*,) are attached for containing the ears and the frame is covered with fur in this case but can be covered with cloth or any other material if desired, and when the muff is used the ears 55 are placed in the pockets *f, f*, which holds the other portion of the muff to the cheeks and chin as fully represented in Fig. 4.

55 Fig. 2, represents a muff made without the wire frame around the cheeks and chin but 60 rings (*g, g*,) are used to form the pockets (*f, f*,) and the cheek and chin portion of the muff are attached to the rings as represented in Fig. 2, and applied to use the same 65 as Fig. 1, muff.

65 What I claim as my improvement and desire to secure by Letters Patent is—

70 The arrangement of the ear, cheek and chin, pieces constructed as represented in Fig. 1, of the drawings, and joined together in the manner represented and for purposes specified in the foregoing specification.

WM. P. WARE.
